COIN BOX

Hildaur L. Neilsen and Michael J. Feis,
Metuchen, N. J.

Application May 23, 1950, Serial No. 163,771

6 Claims. (Cl. 206—0.83)

1

This invention relates to a coin box for holding a predetermined number of coins and more particularly to a coin box which facilitates the handling and counting of coins.

Any activity which is concerned with the use of a sizeable amount of small change is confronted with certain common problems of accuracy and efficiency. People who handle the coins generally must spend considerable time in counting each piece and often this effort is duplicated by the next person who is charged with handling because he will desire verification of the amount turned over to him. Frequently, too, the person counting the money will roll coins of different denominations in special paper wrappers for convenience of further handling so that a predetermined sum is contained in each package. This, of course, adds to the cost and time of the operation, and the count cannot be verified accurately without breaking open the packages. Though automatic machines are available to count coins, these are expensive and usually are not provided for everyone who may need them.

The following is an example of a system which is in common use in retail stores where large numbers of sales clerks are employed on the premises. Each sales clerk is given a certain number of change-making coins of each denomination at the beginning of the day, the coins having been individually counted and wrapped by the cashier's office. The sales clerks open the packages and recount the coins before placing them in cash registers for change-making purposes. The money collected by the clerks from sales is also placed in the cash registers, and at the end of the day the total amount of money is counted and taken to the cashier's office where it is again counted. The total should equal the amount of cash sales made by each sales clerk during the day plus the amount of change-making cash initially received by him.

It has been found that large organizations annually lose substantial amounts of money as a result of this complicated system. Time is unnecessarily lost and effort duplicated because the cashier has to count the coins and then wrap them, only to have the clerks unwrap the coins and recount them. At the end of the day, when clerks are in a hurry to leave, it is necessary for them to collect the loose coins and individually count them before returning them to the cashier for final check. This is a nuisance and leads to inaccuracy, whereas if done earlier customers are sometimes neglected or the clerks become confused from simultaneously waiting on

2

customers and attempting to accomplish their accounting duties. In addition, the cashier again has to go through an elaborate counting procedure to verify the coins returned by the clerks.

Accordingly, it is an object of this invention to provide a coin box in which a predetermined number of coins may be stacked without having to count them individually. Another object is to provide a coin box of the above character which will eliminate the necessity of wrapping coins. A further object is to provide a coin box of the above character which will allow a sales clerk to determine quickly and accurately the number of coins therein without handling them.

A still further object is to provide a coin box of the above character which may be conveniently inserted into a conventional cash drawer of a cash register, so that change may be quickly and easily made from the coin box. Another object is to provide a small, sturdy, and relatively inexpensive coin box of the type described which can be used in a simplified method of counting and handling coins by each person who handles such money. Other objects will be in part apparent and in part pointed out hereinafter.

The invention accordingly consists in the features of construction, combinations of elements, arrangements of parts, and relation and order of each of the same to one or more of the others, all as will be illustratively described herein, and the scope of the application of which will be indicated in the following claims.

In the drawings, in which one form of our invention is shown:

Fig. 1 is a perspective view of a coin box with the cover removed from the body member of the box;

Fig. 2 is an enlarged top plan view of the body member shown in Fig. 1;

Fig. 3 is a sectional elevation taken along line 3—3 of Fig. 2, with the cover in position on the body member, and showing the compartments for holding coins of different sizes;

Fig. 4 is a sectional elevation taken along line 4—4 of Fig. 3, in which the quarter and half dollar compartments are illustrated in further detail;

Fig. 5 is a fragmentary section taken along line 5—5 of Fig. 2, with the cover on the body member, and showing in further detail the construction of the compartment for half dollars;

Fig. 6 is a fragmentary section taken along line 6—6 of Fig. 3, further showing how the cover fits on the body member;

Fig. 7 is an enlarged fragmentary section taken along line 7—7 of Fig. 2 illustrating the locking features which hold the cover in closed position on the body member; and

Fig. 8 is a perspective view of the coin box shown in Fig. 1, with the cover in place and with several coins in each compartment to illustrate the displacement of coins by the cover for counting purposes when the box is tilted forward.

Similar reference characters refer to similar parts throughout the several views of the drawings.

Referring now to the drawings, the coin box has a body member, generally indicated at 10 (Fig. 1), and a cover, generally indicated at 12, which fits on the body member in a manner hereinafter to be described. The body member 10 has a plurality of compartments 14a—14d (Fig. 3) which hold pennies, nickels, dimes and quarters, respectively. Spaced slots 16 (Fig. 2) are provided along the bottom of each compartment, thereby partially exposing alternate groups of coins to facilitate their being counted by a special device disclosed in copending application Serial No. 164,705, filed May 27, 1950. Recesses 18 (Figs. 1 and 3) corresponding in position to the slots 16 are provided in cover 12 to permit a quick and accurate visual check of the number of coins. A slot 20 extends through body member 10 between compartments 14b and 14c so that the body member may rest on a partition in the cash drawer of a cash register and coat therewith in the manner disclosed in copending application Serial No. 163,772, filed May 23, 1950.

More particularly, body member 10 and cover 12 are preferably made from a transparent plastic material to permit the coins to be seen easily. The body member has front and rear walls 22 and 23, and flanges 22a and 23a (Fig. 2) extend outwardly from the top of walls 22 and 23 to grip cover 12 as it is inserted onto body member 10. Slot 20 extends from the lower edges of walls 22 and 23 to flanges 22a and 23a and is positioned between compartments 14b and 14c. The upper edge of wall 23 is rounded as at 23b (Fig. 6), adjacent compartments 14a and 14b, to allow insertion of a fingertip to facilitate removal of the stacks of coins which nearly fill these compartments; the inside of wall 22 has inwardly extending vertical ribs 22b for the same purpose. Body member 10 also has side walls 24 and 25 (Fig. 3) provided with flange portions 24a and 25a; a detent 24b (Figs. 1 and 7) projects upwardly from flange portion 24a to lock cover 12 when it completely closes body member 10.

The channels of compartments 14a—14d extend between walls 22 and 23 and are formed by arcuate walls 26a—26d (Fig. 3), respectively, which have a diameter corresponding to a coin of a particular denomination. Thus, a plurality of stacked pennies may be snugly positioned in compartment 14a, nickels in compartment 14b, dimes in compartment 14c, and quarters in compartment 14d. Arcuate walls 26a—26d are separated from each other by strips 28 (Figs. 2 and 3) integral with flange portions 22a and 23a, and the bottom surface of each wall is reinforced by rectangular strips 30 integral with the walls. The slots 16 provided at the bottom of compartment 14a, 14b and 14c have a length greater than the thickness of four stacked coins and a spacing permitting alternate groups of five coins to be displaced from each other in a manner hereinafter to be discussed more fully. Preferably, the number of coins that may be contained in each of

these compartments 14a—14c is a multiple of five so that each subdivided group may have five coins. Compartment 14d for quarters is provided with slots 16 of such size as to allow displacement of alternate groups of four coins so that even dollar values are obtained.

A half dollar compartment 14e (Figs. 2, 4, and 5) is provided adjacent to and at the rear of compartment 14d, and is separated from compartment 14d by a partition 36. Compartment 14e has arcuate wall portions 26e (Fig. 5) which define at the bottom an opening 38 extending throughout the width of the compartment (Fig. 4). Opening 38 is preferably large enough to receive the fingertip so that the coins may be elevated to facilitate removal thereof. The number of half dollars which can be held in compartment 14e is relatively small and so can be determined quickly even though the coins are preferably not subdivided into smaller groups as in the other compartments.

Recesses 18 (Figs. 1, 3, and 4) in cover 12 correspond in width and position to slots 16 in body member 10 and permit the coins in each compartment to be subdivided into smaller groups for easy and reliable determination of the number of coins in the compartments when the box is tilted as illustrated in Fig. 8 with cover 12 in proper closed position.

Cover 12 is also provided with guides 40 (Figs. 1 and 6) formed by downwardly depending flanges 40a which are inwardly turned as at 40b. Guides 40 engage flanges 22a and 23a on body member 10 as cover 12 is slid along the body member. The cover also has a notch 42 (Fig. 7) formed therein which releasably receives detent 24b to keep the coin box closed.

Calibrations 32 (Fig. 2) visible through cover 12 and indicating cash value are engraved on the top of body member 10 along the sides of compartments 14a—14d to facilitate counting. Similar calibrations 34 are placed on the undersides of strips 30 (appearing backwards when observed from above as in Fig. 2) so that the number of coins in each compartment may be ascertained readily whether viewed from the top or bottom when groups of coins are displaced by the method illustrated in Fig. 8.

The capacity of compartment 14a is fifty pennies, and the five slots 16 and five recesses 18 for this compartment are gauged to permit displacement of alternate groups of five coins each, while calibrations 32 and 34 are struck off accordingly. Compartment 14b has a capacity of forty nickels or two dollars in value, and has four slots, four recesses, and calibrations for the purposes above mentioned. Compartment 14c is calibrated and provided with slots and recesses for fifty dimes, or five dollars in value, and though the capacity is greater, it is preferably not used in deference to obtaining a fixed, even amount of money. The quarter compartment 14d is designed for counting alternate groups of four coins each, or even dollar values, and is provided with but two slots 16 because generally not over five dollars (or twenty coins) in quarters are needed by a sales clerk in starting the day's activities. Nevertheless, this compartment may hold forty quarters and is calibrated and provided with five recesses 18 in cover 12 (Figure 1) for counting when filled to capacity.

Organizations using a large amount of change find it convenient to distribute these boxes each containing twenty quarters, fifty dimes, forty nickels, and fifty pennies, or \$12.50 in value. This has in many cases proved to be an ideal

distribution of change to begin sales activities, and the total amount of money handed out is quickly ascertained on counting eight boxes per one hundred dollars in change.

A typical routine for a department store is as follows:

At the beginning of the day each clerk is given one coin box which contains a predetermined number of coins to be used in making change for sales transaction. In some businesses a certain denomination is not required, in which case that compartment would be left blank. Many stores also distribute several one dollar bills along with the change, and this may be accomplished in conjunction with our coin box by several different ways. For instance, the bills may be placed in a separate envelope, or the coin box and bills may be placed together in a small metal strong box. If a certain denomination of coin is not distributed, the blank compartment could be used for rolled bills. Finally, the coin box may be equipped with a special clip or plastic shelf along the bottom for holding bills securely to it (such a device is not shown in the drawings), this type being useful with a "one bank system," i. e. where clerks turn in and receive back their own money, the cashier providing safe care overnight and having a visible check on the contents.

After a clerk receives a loaded coin box, to verify the coin cash he need only tilt the coin box forward at an angle (see Fig. 8) so that the stacks of coins become displaced in the cover recesses. Tapping the cover may be helpful in urging complete and orderly displacement, and at an instant the exact amount of change can be verified by observation through either the top or the bottom of the box. The calibrations along the side are helpful, particularly when using this method for the first time, but with only a little practice anyone is able to perform the counting operation with very little difficulty. Since the same numbers of each coin are distributed every day, clerks quickly become accustomed to determining the amount of money received by taking a glance without even using the calibrations (it is common knowledge that because of thickness variations the number of coins in a stack can never be determined with certainty by a length measurement alone, and for that reason the calibrations should be relied upon only for a general estimation). Real accuracy is possible only by counting, and this is made very simple and speedy by the described method of segregating the coins into small groups which need not be counted separately because, psychologically, disuniformity in an orderly arrangement is easily observed.

After receiving and checking his money, the clerk may next place the coin box in a cash register cash drawer and dispense change from it directly after the cover is removed, as disclosed in co-pending application Serial No. 163,772 dated May 23, 1950, or he may empty the contents into the various separate compartments of the cash drawer.

At the end of the day, each clerk is required to deposit his money with the cashier, and the coin box is used both for counting and transporting coins. A spare box may of course be made available for overflow if a large amount of change accumulates during the day.

A deposit slip is usually filled out and submitted to the cashier by every clerk, and then the cashier verifies each deposit either by making a visual examination according to the method outlined above using the covered coin box, or with the

apparatus described in co-pending application Serial No. 164,705 dated May 27, 1950. At the same time he can adjust the contents of each compartment in accordance with the store's standard practice so that the correct amount of change remains in the box for distribution the following day.

There is thus provided a coin box in which coins may be stacked without any necessity for counting each coin. When the coin box has been loaded, its contents may be determined simply and accurately by either the sales clerk or the cashier without having to handle the coins, eliminating the need for an elaborate double check.

15 The coin box may be inserted in a conventional cash drawer of a cash register and change on sales can be made directly from it.

Since many possible embodiments may be made of the features of the above invention and since 20 the article herein described may be varied in various parts, all without departing from the scope of the invention, it is to be understood that all matter hereinabove set forth or shown in the accompanying drawings is to be interpreted as 25 illustrative and not in a limiting sense.

What we claim is:

1. A coin box having a body member and a cover formed of transparent material, means forming a plurality of elongated compartments in said body member, each of said compartments proportioned to hold a number of coins in axially aligned relationship when said box is in a normal position wherein the bottom of the box is substantially horizontal, and said transparent cover having a series 35 of rows of recesses formed in the underside thereof, said rows respectively aligned with said compartments to subdivide said coins into small groups to facilitate counting the number of coins in each compartment when said box is tilted from said normal position.

2. A coin box comprising, in combination, a body member, a cover formed of transparent material, means in said body member defining a plurality of elongated channels having continuous 40 smooth portions each adapted to hold a stack of coins of a particular denomination in axial alignment when said box is in normal position, and coacting formations on said body member and cover to detachably and slidably secure said cover to said body member, said cover having a series 45 of spaced recesses in its inside surface disposed longitudinally over said channels when said cover is in closed position, whereby groups of coins may be displaced from their adjacent coins by inverting said body member to form alternate groups of raised and lowered coins in said elongated channels.

3. A coin box having a plurality of elongated channels each adapted to hold a stack of coins 50 of a particular denomination in axially aligned relationship, and a transparent cover fitting slidably onto said box to close said box, said elongated channels having a plurality of slots uniformly separated from one another along the length of 55 the channels to partially expose alternate groups of coins, and said cover having a plurality of spaced recesses formed in its inside surface corresponding in number and registering with said slots when said cover is in place to close said box, said 60 slots being aligned and in parallel rows to receive a multi-pronged tool the prongs of which upon insertion displace groups of coins from each stack toward said recesses to facilitate counting.

4. A coin box comprising, in combination, a 65 container formed of transparent material having

therein an enclosed elongated pocket for coins of a particular denomination arranged flatwise successively along the axis of said pocket, said pocket having continuous unbroken arcuate side wall surfaces of substantial area defining a main channel part of a dimension, smoothness and shape permitting free axial movement of said particular coins for the length of the said pocket when the container is in a normal position wherein the bottom thereof is substantially horizontal whereby said coins may be freely stacked in said main channel part in coaxial alignment throughout the length thereof and a series of spaced recesses offset laterally from and communicating with said main channel portion of a shape and character whereby upon appropriate tilting of the container from said normal position in the direction of said recesses alternate groups of coins may gravitate edgewise into said recesses, with the intervening groups of coins restrained in axial alignment in said main channel portion and the coins may be observed and readily counted by reason of the said transparency of the material and the staggered relation of the successive groups of coins.

5. A coin box comprising, in combination, a container formed of transparent material having therein a plurality of enclosed elongated pockets each adapted to hold a series of coins of a particular denomination arranged in a stack along the axis of the pocket, each pocket having a main channel portion and a series of spaced recesses offset laterally from and communicating therewith, said main channel portion being of a shape and cross section and having side walls of substantial area other than at said recesses and opposed thereto which are smooth and unbroken in the longitudinal direction whereby the particular coins may be freely moved axially for the length of the said main channel portion and readily stacked therein in coaxial alignment for the full length of the pocket when the container is in a normal position wherein the bottom thereof is substantially horizontal, said offset recesses each having a dimension parallel to the axis of the pocket equal substantially to the combined thickness of a predetermined plural number of the particular coins and the distances between recesses being also equal substantially to said dimension whereby the corresponding wall section of the said main channel portion presents alternate radially disposed openings and intervening rib parts and upon appropriate tilting of the container from said normal position in the direction of said recesses alternate groups of coins may gravitate edgewise into said recesses, with the intervening groups of coins restrained in said main channel portion by the respective said rib parts and the coins may be observed and readily counted by reason of the said transparency of the material and the staggered relation of successive groups of the coins.

6. A coin box comprising, in combination, a container having therein a plurality of enclosed elongated pockets each adapted to hold a stack

5 of coins of a particular denomination arranged axially with respect to each other successively along the axis of the pocket, each pocket having a main channel portion and a series of spaced recesses offset laterally from and communicating therewith, said main channel portion being of a shape and cross section and having side walls of substantial area other than at said recesses and opposed thereto which are smooth and unbroken in the longitudinal direction whereby the particular coins may be freely moved axially for the length of the said main channel portion and readily stacked therein when the container is in a normal position wherein the bottom thereof is substantially horizontal, said offset recesses each having a dimension parallel to the axis of the pocket equal substantially to the combined thickness of a predetermined plural number of the particular coins and the distances between recesses being also equal substantially to said dimension whereby the corresponding wall section of the said main channel portion presents alternate radially disposed openings and intervening rib parts and upon appropriate tilting of the container from said normal position in the direction of said recesses alternate groups of coins may gravitate edgewise into said recesses, with the intervening groups of coins restrained in said main channel portion by the respective said rib parts, at least one of the walls of the pocket being transparent to enable the coins to be observed and readily counted by reason thereof and the staggered relation of successive groups of the coins.
